UNITED STATES PATENT OFFICE

2,233,431

ELECTRICAL VAPORIZER

Joseph Robinson, New York, N. Y.

Application February 18, 1936, Serial No. 64,475
Renewed August 16, 1939

4 Claims. (Cl. 128—192)

This invention relates to vaporizers of the individual hand type for use in generating vapors for direct inhalation in the treatment of head colds, catarrh, sinus infection, asthma, hay fever, 5 and other afflictions of the respiratory organs. The invention is an improvement on the construction shown in my United States Letters Patent #2,197,840, granted Apr. 23, 1940, and among its objects are the reduction of manufacturing costs; 10 the provision of simple and improved means for anchoring the switch blades of the vaporizer in place, and the provision of a combination container and sleeve in which the container, in one form of my improvement, is relatively shallow 15 and may be used either as a container for the medication to be vaporized or as a support for a discardable pellet or wafer that contains the medication.

In the drawing, 20 Figure 1 is a vertical section through my improvement, some of the parts being shown in elevation;

Figure 2 is a plan view of the construction shown in Figure 1 with the cap F removed;

Figure 3 is a sectional plan view on approximately the line 3—3 of Figure 1;

Figure 4 is a sectional detail of the bottom of the base A of my improvement showing a portion of the blade 16, and one of the terminals 21 in 30 front elevation;

Figure 5 is a side or edge view of the contact blade 17 showing the curved formation of the lower end 18 of the blades before they are put in place.

My improvement includes an elongated hollow base A, which is tapered practically throughout its length. In its lower portion the base is provided with inwardly projecting lugs or shoulders 7, Figure 3, which are reinforced by upwardly inclined brackets 8. Between these brackets the lugs are provided with suitable vertically arranged rectangular sockets or bearings 9 of proper size and depth, as shown. The usual electric cord B extends into the base A through the bottom thereof, and is knotted at 10 to free its terminals 11 of undue strains. The terminals are suitably anchored to the ends of the strands 12 of the cord and have flat turned back portions 14, and feet or lugs 15 that extend at substantially a right angle to a vertical plane. The terminals are inserted in the sockets 9 and are firmly anchored in place by vertically extending resilient switch blades 16—17. The lower end of each of these blades is normally curved, at 18, Figure 5, the 50 curve being straightened out as the blades are

forced down into the sockets or bearings 9. In this way a considerable amount of spring tension and friction are produced between the terminals, the blades and the rear wall of the openings. The friction or tension is of such extent as to firmly 5 but removably secure the blades and the terminals in the assembled position shown in Figure 1, and to prevent the blades moving laterally or vertically unduly in the bearings 9. To further assure proper lateral positioning of the blades I 10 provide for the blade 17 a vertically extending groove 19 in the wall of the base A and turn the upper end 20 of the blade into this groove, and in the case of the blade 16 I turn its upper end 21 abruptly inwardly across the vertical center 15 line of the base A and perforate it on this center line to receive the lower portion 22 of the heater C shown in my aforesaid co-pending application. In the assembled position shown in Figure 1 the projection 21 of the blade 16 is vertically compressed or deflected to assure constant contact 20 between it and the heater C. It will be noted that the blades 16—17 lie closely along the inner walls of the base A, and that the blade 16 bears against the base at 23 to form a support for the blade. 25

The heater C rests on top of the base A and is anchored to it by the two piece combination sleeve and receptacle or container D which fits tightly over the upper end of the base and is firmly secured thereon, in liquid tight relation thereto, by crimping or turning the lower edge 24 of the sleeve over a shoulder formed for the purpose on the base A. The upper end 25 of the sleeve is turned over a shallow receptacle 26, the connection between the receptacle and the sleeve being 30 liquid tight, and the bottom of the receptacle being drawn tightly against the upper insulated face of the heater C by the crimping operation described. The receptacle 26 directly receives a medication, when desired, and serves as a support for a medicated, or medicine filled, pellet E of any suitable construction. I show this pellet in the form of a small metallic container having a cover 27 centrally perforated as shown. A suitable cover or cap F, having a mixing chamber 28, sits loosely down over the combination receptacle and sleeve D, insulates against the heat of the sleeve, and is provided with a plurality of vertically extending serrations 29 which at their upper end turn inwardly over the top of the pellet E, similar to the arrangement shown in my aforesaid co-pending application. The construction 40 construction forms, at the bottom of the mixing chamber 28, a shoulder that extends over the 45 50 55

pellet and serves to position the cover F on the vaporizer and to retain the pellet in place.

In assembling my invention the cord B is inserted in the base through the opening in the latter, the terminals 11-14 being small enough to pass through the opening in the bottom of the base. The cord is shoved entirely through the base and is then knotted whereupon it is drawn back to the position shown in Figure 1. The switch button 35 is then inserted, its head 36 occupying the groove 19. The blades 16-17 are then pressed into place, after which the heater C is mounted on the upper end of the base A with its lower portion 22 passing through and engaging the inwardly turned angularly disposed projection 21. The inclination of this projection holds the heater off its seat on the base A until the combination receptacle and sleeve D is set over the heater, and over the upper end of the base A, and is drawn tightly down into place by crimping its lower edge 24 over a shoulder on the base, as hereinbefore described. This operation serves to draw the sleeve and the container 26, firmly into place, straightening out the projection 21 of the blade 16 to the horizontal position shown in Figure 1, and pressing the blade tightly in its groove in the lug 7.

When it is desired to vaporize a medicament with the preferred form of my improvement, the medicament is either placed in the container or the medicated pellet or wafer E, which is preferably packaged in quantities, is placed in the container or receptacle 26. The switch button 35 is then pressed in, which throws the upper end of the blade 17 against the contact washer 36 of the heater C and lights the heater, the thin walls of the pellet E expediting the vaporization of the medicament. When vapors are produced, the tip 37 of the cover F is placed in the nasal passage, and on inhalation currents of air are drawn into the vents or ways 29 and are heated as they travel up along the hot walls of the sleeve D into the hollow chamber 28 of the cover F. Here the heated currents of air meet and lift the vapors, while hot, into the nasal passage.

What I claim is:

1. An electrical vaporizer comprising in combination, an elongated hollow base provided with a horizontally arranged seat on its upper portion, a pair of vertically arranged sockets or bearings formed on the interior of said base adjacent to the bottom thereof, a heater mounted on said seat and positioned horizontally thereby, a receptacle for a substance to be vaporized, said receptacle being fitted tightly to the upper end of said hollow base in retaining relation to said heater and in liquid tight relation to said base, a nasal part set over said receptacle and insulating the same and serving to direct the vapors to the nasal passage, an electric cord extending into said base from the lower end thereof, and a pair

of resilient switch blades mounted in said sockets and frictionally removably held therein, said blades being in contact with said cord and adapted to conduct current therefrom to said heater, one of said blades being in constant engagement with said heater and the other being normally disengaged from said heater and adapted to be manually pressed against the heater to close the circuit.

2. An electric vaporizer such as described in claim 1 in which the terminals of the electric cord are also mounted in said vertical sockets, said terminals being frictionally removably held in said sockets in circuit contact with said blades when the blades are placed in the sockets.

3. An electrical vaporizer comprising in combination, a base having an exterior annular bearing at its upper end which bearing terminates in a shoulder, said base being provided adjacent its lower end with an interior socket for a switch blade, a heater mounted on said base, a receptacle for a substance to be vaporized, said receptacle being turned back on itself into a cup which engages said heater, a cover set over said receptacle and insulating the receptacle and serving to direct the vapors, an electric cord extending into said base through the lower end thereof, an elongated resilient switch blade mounted in said socket and frictionally removably held therein, said blade being connected with said cord and adapted to conduct current therefrom to said heater, and a common means for clamping said heater and said receptacle to said base and for maintaining the heater in place with respect to said switch blade and said base, said means comprising a sleeve or flange depending from said receptacle, said sleeve or flange being tightly fitted to said annular bearing with its lower edge crimped or spun over said shoulder to draw said receptacle down against said heater and to clamp the receptacle and the heater in liquid tight relation to each other and to said base, said receptacle serving also to prevent dislodgement of said switch blade from said socket in event the blade moves upwardly in the socket during use.

4. An electrical vaporizer comprising in combination, a receptacle for a medicament to be vaporized, means for directing the vapors of said medicament to the nasal passage of a user, a base, a heater mounted on the base for heating the medicament, a terminal, and friction means for holding said terminal in place with respect to said base, said means including a socket and a resilient blade adapted to conduct current to said heater, said blade being frictionally held in said socket and being deflected laterally to engage said heater in a way to subject the blade to constant pressure and prevent displacement of the blade with respect to said socket.

JOSEPH ROBINSON.
